UNITED STATES PATENT OFFICE.

JOHN A. THOMAS, OF LANSING, MICHIGAN.

FIRE-FIGHTING APPARATUS.

1,152,452.

Specification of Letters Patent.

Patented Sept. 7, 1915.

Application filed January 2, 1912. Serial No. 668,824.

To all whom it may concern:

Be it known that I, JOHN A. THOMAS, citizen of the United States, residing at Lansing, in the county of Ingham and State of Michigan, have invented certain new and useful Improvements in Fire-Fighting Apparatus, of which the following is a specification.

This invention has reference to fire fighting apparatus, and the invention consists specifically in an engine having a pump adapted to force the water upon the fire and a receptacle for chemical connected with the suction and supply side of the pump, and is an improvement on the means shown and described in my application for Letters Patent of the United States, filed October 27, 1911, and bearing Ser. No. 657,031. In the said application the chemical mixture is delivered to the stream of water by means of a series of pumps which are designed to accumulate a sufficient force to overcome the back pressure in the line of discharge and thus drive the chemical solution perforce 25 into the outgoing stream.

The present invention contemplates the simplifying of the mechanism of the engine and its proportionate cheapening in actual cost by dispensing with the said series of 30 pumps and substituting a suction draft between the chemical supply chamber or receptacle and the receiving or inlet side of the engine pump. This also has the material advantage of utilizing the said pump as a mixing medium for the chemical, which 35 is drawn or sucked forward by said pump and thoroughly incorporated with the stream of water passing through the same to the hose, as also will hereinafter more fully 40 appear.

The accompanying sheet of drawings is a representation of the mechanism directly involved in this invention and comprises a cross section of the engine pump, a sectional elevation of the chemical feed and saturating devices and the pipes and parts associated therewith and which are more or less arbitrarily disposed or related one with the other but serving present purposes.

In detail the engine pump is represented by P, and which has a casing 2 with one or more water inlet or supply connections 3 and an internal chamber 4 in which there are two rotary intermeshing members 5 supported on shafts 6 and 7 respectively, and adapted to be driven by power applied

through one or the other shaft, say shaft 6. The water is pocketed in the said members or rotors and carried up about the outside thereof next to the casing 2 and delivered to 60 the outlet or discharge connection 8. The said rotors are provided with a series of wings *a* intervening depressions *b* forming pockets to carry the water and are connected up to rotate in opposite directions and run 65 in such close relations to the casing 2 that they make practically water tight working engagement therewith, more or less after the fashion of rotary pumps. The said rotors of course are supposed to travel at such 70 speed that they will create and maintain the highest needed pressure in the hose 10 whatever such pressure may be, and the degree or measure of pressure will be under the control of the engineer. It is not 75 therefore material whether the supply of water be under pressure, and presumably the draft upon the supply in any event will be such as to become more or less exhaustive and therefore cause suction in the inlet line 80 for the water. I have therefore availed myself of this disposition or effect by arranging to take the chemicalized liquid from the saturating chamber 12 directly by suction through pipe 13 to the supply or intake side 85 of the pump, while the saturating liquid or water is delivered to the said chamber 12 from the discharge side of the pump by pipe 15. The latter pipe has a hand controlled regulating valve 16, while delivery 90 pipe 13 has a back check valve 17, as to the pump. These or other valves may be used in the said pipes as experience may suggest, it being of course understood that in any event the saturating chamber 12 is not 95 intended to be filled with water at any time and in fact it has an overflow connection 18 at its top to avoid possible backing up of the water into the chemical feed.

In the present construction I plan to use 100 common bi-carbonate of soda as the chemical agent, and the supply is through bin or hopper 20 or other means to the cylinder or casing 21 and the worm conveyer 22. Of course it will follow in the foregoing organization that the water delivered to the chamber 12 by pipe 15 will be chemicalized to the maximum of the outflowing stream to the fire, but that fact will not affect saturation of the dry chemical fed to said chamber 110 in predetermined and uniform proportions, to the end that the volume of outgoing water

shall carry the same amount of chemical all the time and in perfect admixture with the water. Obviously the solutions cannot pass through the pump and the line of connection to the hose nozzle without becoming thoroughly mixed with the water and so that it will reach the fire under the most favorable conditions. This also is one of the advantages of passing the chemical solution 10 through the pump.

Just what the proportions are is not a matter for consideration herein, and the relation of the parts for effecting the admixture need not necessarily be as shown, as is 15 obvious. However, this is essential to the present invention, that the delivery of the chemical solution be on the intake side of the pump and preferably by suction, and its supply may be increased by raising the 20 chamber to a higher elevation for greater gravity pressure or the equivalent of such pressure from any other source may be adopted. In the present case I am assuming that suction will do the work, and as an auxiliary to this operation I show the extremity 25 of the delivery pipe or connection 13 as extending into the pump casing and directly to the immediate inlet for the water to the rotor chamber where the suction is emphasized. The axial depth of the rotors may be 30 varied, but the relation of the said extension to the said inlet is not such as to really constitute an obstruction, and constitutes the equivalent of a nozzle or nipple which 35 might have a more or less reduced delivery.

Of course the chemical might be delivered to the water supply at some other point than through the pump casing, and I may arrange to force the dry soda into the volume of water entering the pump and thus dispense with the receptacle or chamber 12, but I find the present arrangement preferable on several accounts.

I may also employ a force pump in the pipe line 13 and drive the chemical solution 45 into the water that passes through the main pump. All these ways have been considered and been more or less satisfactorily demonstrated in various tests.

What I claim is:

In a fire-fighting apparatus, a force pump having a pair of rotors and a single inlet, a plurality of water supply connections leading to said inlet and a single discharge connection for said pump, in combination with a chemical mixing receptacle having water-supply communication with the discharge connection of said pump and provided with a delivery connection for the chemical solution extending through said 55 water supply connections directly to said inlet.

In testimony whereof I affix my signature in presence of two witnesses.

JOHN A. THOMAS.
